PORTABLE POWER PACK

Ralph M. Foecking, Rocky River, and Jack E. Wenink,
Olmsted Falls, Ohio, assignors to Union Carbide Cor-
poration, a corporation of New York

Filed Dec. 21, 1962, Ser. No. 72,940

Term of patent 14 years

(Cl. D26—15)

FIG. 1 is a perspective view showing the top, front and one side of a portable power pack embodying our design. The electrical socket for the portable power pack is shown in broken lines for illustrative purposes only.

FIG. 2 is a perspective view showing the top, back and the other side of the portable power pack, the bottom being substantially identical to the top.

We claim:

The ornamental design for a portable power pack, as shown and described.
